UNITED STATES PATENT OFFICE

MARCH E. NAGLE, OF CHICAGO HEIGHTS, ILLINOIS, ASSIGNOR, BY MESNE ASSIGNMENTS, TO OWENS-ILLINOIS GLASS COMPANY, OF TOLEDO, OHIO, A CORPORATION OF OHIO

GLASS-STOPPER MACHINE

Application filed December 8, 1924. Serial No. 754,469.

My invention pertains to machines for the manufacture of glass peg stoppers, such as are commonly used with bottles containing perfume and which are usually of more or less ornamental design, and for the production of similar articles of commerce.

One object of the invention is to provide improved means for discharging the cast stoppers from the molds or for elevating them sufficiently so that they can be easily removed.

A further purpose of the invention is to supply a mold construction of such character that several types or styles and sizes of stoppers may be molded or cast simultaneously without danger of the production of objectionable fins at the parting line or plane of the sections of the mold.

Another aim of the invention is the production of an appliance of this character having a plurality of mold-sections adapted to cooperate successively with a single complementary mold-section, whereby an effective time saving is possible since the mold-sections of the series may be simultaneously undergoing different operations incident to the molding or casting action, for instance, one mold-section may be receiving its charge of molten glass, another performing the molding operation, and a third delivering its cast articles. Such a construction permits the mold-section common to the several others to be water-cooled and the latter to be air-cooled because they undergo the heating influence comparatively infrequently.

For the accomplishment of these and other objects, I have devised a novel machine, representing a desirable and preferred embodiment of the invention, which I have illustrated in detail in the accompanying drawings forming a part of this specification and throughout the several views of which like reference numerals have been employed to designate the same members.

In these drawings:

Figure 1 shows most of the machine in elevation with a part thereof in vertical section;

Figure 2 is a horizontal section on line 2—2 of Figure 1;

Figure 3 gives a central vertical section on an enlarged scale through the upper and lower mold-sections and their associated plungers, one of the latter being illustrated in section and the other in elevation;

Figure 4 is a top plan view of one of the lower mold-sections with certain parts in section;

Figure 5 is a horizontal section on line 5—5 of Figure 3;

Figure 6 is a plan view of the under face 60 of the upper mold-section;

Figure 7 is a horizontal section on line 7—7 of Figure 1;

Figures 8 and 9 are views of the ejector mechanism;

Figure 10 is an enlarged, fragmentary, vertical section indicating one of the molds for producing glass stoppers with undercut characteristics requiring a supplemental movable mold part retractable to permit discharge of the cast stopper;

Figure 11 shows the cooling water connections for the upper plunger; and

Figure 12 is a perspective view of a stopper having undercut portions requiring the employment of a mold having the structural features indicated in Figure 10.

Referring to these drawings, it will be perceived that the appliance includes a suitable frame or table 21 with upstanding, guide rods or bars 22, 22 adapted to guide the upper, reciprocable, mold-section characterized as a whole 23.

A revoluble table-top or turret 24, which may be intermittently rotated or turned step-by-step manually or in any other approved manner, carries five, or any other appropriate number, of lower mold-sections 25, 25.

Such table element may be conveniently equipped with rollers 26 travelling in a cir-

cular trackway 27, whereby the mold-carrying table member may be easily turned to bring the lower mold-sections successively below, or into cooperative relation with the single, companion, upper mold-section.

Inasmuch as all of the table mold-sections are alike, a complete illustration and description of one will suffice for all.

Each such mold-section 25 comprises a circular base 28 having a central round bearing 29 and a plurality of vertical holes or recesses 31, 31 adapted to receive positioning-pins 32, 32 mounted on and projecting upwardly from the upper surface of the revoluble supporting-member 24, whereby the mold-section may be demountably applied in correct position on such member.

Above such base, I provide a main-body 33 of round shape having a central bearing 34 in register or coaxial with the lower bearing 29 and having a depending, marginal flange 35 fastened by screws 36, 36 to the base.

The top face of the main-body 33 has an annular channel or groove 37 accommodating a plurality of sector-shaped mold-blocks 38, 39, 41, 42, 43, 44, 45, 46, 47, 48, 49 and 51 having mold cavities in their top faces which, as to their forms and sizes, may be all alike or all different or otherwise.

In the present instance, I have shown twelve such mold-members, but, of course, any suitable or desired member could be employed.

These several, radially-disposed mold-members are securely fastened to the main-body 33 by screws 52, 52, all as is clearly illustrated.

As is fully depicted in Figure 3, the aligned bearings 29, 34 slidingly accommodate a plunger 53 having a top, concave or dished face 54 and having an intermediate, outstanding, round flange 55 supplied on its outer edge with one or more screw-threads 56.

The top face of that circular part of element 33 between the plurality of annularly arranged mold-members 38-51 and the centrally-positioned plunger 53 is equipped with radiating channels or grooves 57 leading outwardly from the center to the sundry half-mold cavities in the mold-members, whereby, as will be explained hereinafter, the molten glass may be forced outwardly through such passages into the mold spaces.

That is to say, a suitable amount of molten glass is deposited in the center of the mold on the plunger 53, and, by means of the upper mold-section 23 and its associated parts, is forced or squeezed outwardly into the twelve molds, so that the glass casting or product comprises a central, saucer-shaped part from which the twelve peg stoppers radiate.

It is necessary to elevate or raise this peculiar-shaped casting from the correspondingly-shaped, lower, mold-section, made up of several parts, and it is for this purpose that

the one or more screw-threads 56 are supplied.

Each of the mold-members, in register with the neck of the glass-stopper cast therein, has a small, vertical, cylindrical hole 58 therethrough to receive the upper correspondingly-shaped part of an ejector 59, the lower portion 61 of which is square in cross-section and vertically slidable in like-shaped, aligned bearings 62 and 63 in the parts 33 and 55 respectively.

On its under face, the horizontal flange 55 has an annular channel 64 into which the lower ends of the ejectors project, such parts of the latter having cross-pins 65 therethrough bearing against the under surface of the wall at the top of such channel so that when the plunger and its flange move down, the several ejector-pins will be positively pulled down simultaneously equal amounts.

In order that the series of ejector-pins may be pushed up all at the same time and equal distances to assist in lifting the cast stoppers from their lower mold-section, their bottom ends rest or bear on a flat ring 66 closing the bottom of the channel and held in place by screws 67.

A ring 68 surrounds the flange and has one or more screw-threads 69 coacting with those of the periphery of the flange whereby partial rotation or turning of the ring will cause the elevation or descent, as the case may be, of the central plunger 53 and the complementary ejector-pins 59, 59.

As is indicated in Figure 5, the flange 35 of the main-body 33 is cut away on one side at 71 and occupying, and adapted to move in, this space is a handle 72 fastened by screws 73, 73 to the outer face of the oscillatory threaded ring 68, and, by means of such handle travelling in the arcuate space 71, the ring may be turned the required amount in the one direction or the other.

Each main-body 33, as is shown in Figure 1, has an outstanding handle 74 secured thereto so that the turnable table may be swung around to bring the lower mold-sections in sequence into register with the single, upper, mold-section.

If the stopper to be cast or molded has an undercut head, for example as shown in Figure 12, and two of which are indicated in Figure 4, it is necessary to make a part of each such mold movable with relation to the two usual sections (upper and lower) whereby it may be temporarily retracted to permit the completed stopper to be removed.

In such cases, the lower mold member, 47 or 49, for instance, has a semi-cylindrical cavity 75, Figure 10, slidingly receiving a cylindrical mold-member 76 movable radially of the multiple mold into operative and into inoperative positions and having an appropriate mold cavity on its inner face to form a portion of the stopper-head.

This mold element 76 has an outwardly-

directed shank 77 square in cross-section and provided with an intermediate recess 78 into which projects the shorter arm 79 of a bell-crank lever fulcrumed at 81, in a cavity in part 33, the longer arm 82 of the bell-crank lever extending into an opening 83 in a horizontal ring 84 surrounding and turnable on the upper part 85 of the body 33 of slightly reduced diameter.

10 This external ring 84 has an outwardly-projecting handle 86 by means of which it may be turned, its movement being limited in both directions by a stationary stop or abutment 87 on the body 33 extending into a slot 15 88 in the ring provided for that purpose.

It should be noted in passing that the outer end of the stem or shank 77 is slightly bevelled at 89 (Figure 10) for a purpose hereinafter stated.

20 The single, upper mold-section 23 is supported from above from a top horizontal cross-bar 91 vertically slidable on the guides 22, 22, the opposite ends of such element 91 being pivotally mounted on a pair of eccentric-rod 92, 92, actuated by eccentrics 93, 93 on a suitably-journalled shaft 94 below the table top and equipped at one end with an operating handle 95 by means of which it may be rocked.

25 Cross-bar 91 is centrally apertured for the reception of the upper end portion of an upright, threaded rod 96, adjustably fixed to the bar by nuts 97 and 98 on the rod bearing against the upper and lower faces of the bar.

30 Also mounted in similar adjustable manner on the rod 96 by a pair of nuts 99 and 101, I provide a substantially-square horizontal plate 102 having four vertical holes therethrough near its corners which slidingly receive the upper end parts of four bolts 103 the heads of which are above and normally support other elements, about to be described, by resting on the top face of the plate.

35 The lower ends of such bolts are screwed into threaded holes in a plate 104, coiled compression springs 105 surrounding the bolts bearing at their opposite ends on the under face of the upper plate and on the top face of the lower plate, whereby the latter may yield or give somewhat upwardly.

40 By means of two screws 106, plate 104 carries beneath it a smaller plate 107, the two being centrally apertured in register for the accommodation of the upper plunger or piston to be described.

45 Also by means of screws 108, plate 107 supports a round body 109 having an annular channel 111 in its top face, covered by a ring 112, and divided by a cross-partition-wall 113 at one point only. (Figures 3 and 6.)

50 Cooling water or other appropriate heat-extracting fluid is admitted to such channel at one side of the division wall through a pipe or tube 114 and the heated water or other fluid is discharged from the channel on the

opposite side of the wall through a tube or pipe 115, all as will be readily understood.

On its under face member 109 has an annular groove 116, corresponding to the groove 37 of the lower mold-section, in which, by means of suitable screws 117, are held the twelve complementary mold-blocks 118, 119, 121, 122, 123, 124, 125, 126, 127, 128, 129 and 131 having mold cavities or recesses corresponding to those of the lower blocks 37, 38, 39, 41, 42, 43, 44, 45, 46, 47, 48, 49, and 51 respectively.

Thus when such upper mold-section is associated with any one of the five lower mold-sections, twelve complete mold cavities will be formed.

As is depicted in Figures 6 and 10, the two, upper, mold elements 127 and 129, corresponding to the pair of lower mold elements 47 and 49 for the production of undercut glass stoppers, have proper, semi-cylindrical cavities for the accommodation of the upper halves of the retractable mold parts 76 as will be easily understood.

Where each such mold is employed, the member 109 is fitted with a downwardly-projecting wedge-block 132 (Fig. 10) which in the closed condition of the mold bears against the end of the shank 77 and holds the movable mold part 76 immovably in proper active position.

A cross-bar 133 is fastened in any approved manner on the lower end of the upright, stationary screw-shaft 96, its opposite ends being notched at 134, 134 to accommodate and be guided by the vertical rods 22, 22.

This bar 133 also has two holes 135, 135 therethrough slidingly receiving two rods 136, 136 fastened to and upstanding from the plate 104 so that the latter and the parts which it carries are correctly guided in their vertical reciprocations.

Bar 133 is fitted with two, pivoted catches 137, 137 (Figure 1), the upper bevelled ends of which cooperate with the conical surface of a nut 138 adjustable on the screw-shaft 96, such nut normally holding the catches in operative or active position, whereby they fit under and support the enlarged head 139 of a top, hollow plunger or piston 141 guided in its vertical movements by bearings 142 and 143 in the members 107 and 109, the bottom of such plunger having a convex surface 144 complementary to the concave face 54.

Internally, plunger 141 has a division-wall 145 (Figure 3) reaching from the top almost to the bottom thereof and the head 139 is equipped with an entrance water-pipe 146 (Figure 1) connecting with the interior of the plunger at one side of the partition-wall 145 and with a water discharge-pipe 147 at the opposite side of such wall, whereby the water flowing through the plunger effectively cools it.

As is indicated in Figure 3, the portion of

the member 109 between the channel or groove 116 and the plunger-bearing 143 is recessed or cut away at 148 at points corresponding to the mold cavities to form suitable channels with the mold recesses in association with the companion registering passageways 57.

In order to register the lower mold-sections, as they are turned into place, approximately with the single, upper, reciprocatory mold-section, the body 33 is provided with a suitable number, in the present instance three, of round holes 151, 151 in its top face and the under portion of the member 109 is equipped with a like number of downwardly-projecting pins 152, 152 designed to enter such cavities.

The final, exact registration, however, is effected by other means, as follows:

20 Member 33 has a slightly-tapered annular-groove 153 extended around its inner edge, but such groove is omitted at three points providing a like number of tapered projections or lugs 154, 154.

25 Member 109, on the other hand, has an inner, tapered, circular rib 155 on its under face cut away at three points 156, 156 to supply that number of slightly-bevelled recesses designed to receive the lugs 154, 154, the 30 groove 153 of course accommodating the rib 155.

A very important feature of the invention has yet to be mentioned.

35 Inasmuch as the hot, molten glass is supplied or forced into the twelve radiating mold cavities from a central supply, the inner portions of the mold-members directly adjacent to such supply become more heated than the outer portions and consequently expand to a greater extent.

It is essential that the upper and lower mold-sections should fit together accurately and closely without substantial space between them at any point, otherwise, particularly 5 under the pressure exerted on the central molten supply of glass to squeeze or force it to completely fill all of the several molds, it will be expressed into such space or spaces forming objectionable fins on the stoppers and rendering them unsatisfactory to the trade.

To secure such precise and exact fit or adaptation of members and the avoidance of the production of the fins or flanges referred to, the top faces of the several lower mold-members 38—51 are slightly inclined so that in very small degree they slope downwardly inwardly toward the center and the bottom surfaces of the correlated, upper 60 mold-members 118—131 incline upwardly inwardly slightly.

Thus, when the machine is in operation, the two sets (upper and lower) of mold-members expand and form a close accurate fit 65 between them throughout the extent of their

contacting surfaces eliminating the possibility or likelihood of any of the molten glass leaking between them, even though it is under great pressure, and producing the detrimental or harmful thin projections specified. 70

At first thought, it would appear that those molds having the greater size of cavity for the manufacture of stoppers of greater dimensions would require more slope or taper of the character stated than those having mold recesses of lesser volume, because of the greater quantities of molten glass which they receive, but I have discovered that this is not true and I have ascertained that those mold-members having the greater amount of 75 metal in them and consequently having the smaller mold spaces are the ones which expand the most.

These, therefore, require a greater degree of slope or inclination or need to be cut away 80 more to produce the required accurate fit between the parts, and they are constructed in this manner.

It is to be understood, therefore, that the numerous mold-members are or may be tapered in varying degree depending upon the shapes and sizes of their mold spaces so that under the action of the heat imposed on them they will all expand in such manner and in such amount as to obtain the comparatively-90 exact, smooth fit between the upper and lower mold-sections, each of the latter, as indicated, having several such mold-members. 95

The operation of the novel machine occurs practically as follows: 100

Assuming that the upper mold-section and its sliding plunger are being cooled by the inflowing and outgoing water, and assuming that by means of the handle 86, all of the previously-retracted, movable, mold parts 105 76, of the lower mold-section 25 in the position indicated as A, Figure 2, have been pushed in into operative position, a correct amount of molten glass is deposited in the saucer-shaped receptacle 54 of the lower 110 plunger 53 while the latter is in its lowered position.

Then the table is swung around one-fifth of a revolution to bring back such glass-charged lower mold element 25 beneath the 115 then-elevated, upper mold element 23.

Thereupon, by manipulation of the operating handle 95, the upper mold-section 23 and its associated plunger 141 are caused to descend until such part 23 rests upon the corresponding lower part 25, their precise registration being assisted by the cooperating elements 151, 152 and 154, 156. 120

Continued downward turning of the handle causes the companion mold-sections to be firmly forced together by the increasing pressure of the springs 105 and the upper plunger, 141 during its further descent, engages the top of the molten glass charge and forces it radially outwardly to fill the twelve, 125 130

complete mold-pockets, whereby there is produced a saucer-like, central, glass body 157 (Figure 3) having twelve radiating stoppers attached thereto, the stem of each of which has a section 158 of materially-reduced cross-section so that the stopper proper may be easily broken off from the central body at this point, the latter being later remelted as part of a subsequent glass supply.

10 Then the top mold-section and its plunger are raised and the table turned another one-fifth of a revolution to bring the lower mold-section 25 under consideration into the exposed position marked B on Figure 2.

15 At this place, an operator moves the handle 86 to retract all of the mold parts 76 simultaneously and then turns handle 72 in such direction as to lift all of the ejectors 59 at the same time, the lower plunger rising simultaneously an equal amount, whereby the central glass body 157 and its plurality of attached molded stoppers are lifted bodily out of the molds permitting their manual removal from the machine at which time the glass 25 has cooled sufficiently to permit the breaking off of the stoppers from their temporary, common, (central) glass support.

At the time of the arrival of such mold-section, during its intermittent rotary movement, at the position A or before reaching such location, the two handles 72 and 86 are turned to lower the ejector-pins and the companion plunger and to push in the mold parts 76 to active position.

30 35 The upper mold-section is adequately cooled by the water specified and the lower mold-sections are also sufficiently cooled by reason of the fact that there is an ample number of them heated in succession with enough time between heating periods for any one so that it does not become unduly heated or over-expanded.

Because all of the ejectors are actuated by a common element, the ring 66, any wear occurring in the operating mechanism of the latter shows its effect equally on all of the ejectors and there is sure to be an equal raising action on all the stoppers and the central body under all conditions, which is desirable or essential to prevent any of the stoppers from breaking off prematurely requiring them to be picked out of the molds individually by hand.

50 55 Those skilled in this art will readily understand that this invention is not limited or restricted to the precise and exact details of structure presented and that many more or less radical changes may be incorporated 60 in the appliance without departure from the substance and essence of the invention and without the sacrifice of any of its material benefits and advantages, for instance, instead of having both of the meeting surfaces of the 65 upper and lower mold-sections inclined or

sloped in opposite directions, the entire inclinations may be provided on either one only of such mold-sections.

I claim:

1. A mold-section having a cavity to receive a charge of molten material and a plurality of mold-recesses communicating with said cavity, the surface of said mold-section adapted to contact with the corresponding surface of a complementary mold-section sloping toward said cavity to compensate for the greater expansion of the part of such mold-section nearest said cavity. 70

2. A mold-section having a central cavity to receive a charge of molten material and a plurality of radiating mold-recesses communicating with said cavity, the surface of said mold-section adapted to contact with the corresponding surface of a complementary mold-section sloping toward said central cavity to compensate for the greater expansion of the part of such mold-section nearest said cavity. 80

3. A mold-section having a cavity to receive a charge of molten material and communicating with a plurality of mold-recesses of different capacities, the surface of said mold-section adapted to contact with the corresponding surface of a complementary mold-section sloping toward said cavity in varying degree depending upon the sizes of the mold-recesses to compensate for the greater expansion of the parts of such mold-section nearest said cavity. 90

4. A mold-section having a central cavity to receive a charge of molten material and including a plurality of separate mold-blocks having mold-recesses of different shapes, said cavity communicating with said several mold-recesses, whereby the latter may receive their supply of molten material from such cavity, the surfaces of said mold-blocks adapted to contact with the complementary surfaces of a companion mold-section sloping toward said central cavity. 100

5. A pair of co-operating mold-sections unitedly forming a cavity to receive a charge of molten material and a plurality of mold-recesses of different capacities communicating with said cavity, the contacting surfaces of said mold-sections sloping toward said cavity in varying degree depending upon the sizes of the mold-recesses to compensate for the greater expansion of the parts of the mold-sections nearest said cavity. 110

6. A pair of co-operating mold-sections unitedly providing a cavity to receive a charge of molten material and a plurality of mold-recesses communicating with said cavity, the contacting surfaces of said mold-sections sloping toward said cavity to compensate for the greater expansion of the parts of the mold-sections nearest said cavity. 120

7. In a machine of the character described, the combination of a pair of separable mold- 130

sections for the production of a main glass body having a plurality of glass-stoppers extending therefrom, a plunger to lift said body from one of said mold-sections, a lifting pin for each of said stoppers to raise them from said mold-section simultaneously with the elevation of said body, and operating means common to said plunger and pins to raise them equally and to lower them together positively, whereby any wear in said operating means equally affects the movements of said plunger and pins.

8. In a machine of the character described, the combination of a mold-section having a central bearing for a plunger and a plurality of radiating glass-stopper mold-cavities communicating with the space above said plunger, a companion mold-section movable relatively to said first mold-section, a plunger reciprocable in said bearing and having an outstanding flange, an ejector for each of said mold-cavities slideable in said first mold-section and connected with said flange to partake of the movements of the latter, means to force a part of a molten-glass supply deposited on said plunger into said mold-cavities, and a single-screw mechanism to raise and lower said plunger and its flange, whereby the central glass body formed above the plunger and the several cast glass-stoppers attached thereto may be raised simultaneously and equally to facilitate their removal from said first mold-section.

9. In a machine of the character described, the combination of a mold-section having a central bearing for a plunger and a plurality of radiating glass-stopper mold-cavities communicating with the space above said plunger, a companion mold-section movable relative to said first mold-section, a plunger reciprocable in said bearing and having an outstanding flange, an ejector for each of said mold-cavities slideable in said first mold-section and connected with said flange to partake of the movements of the latter, means to force a part of a molten-glass supply deposited on said plunger into said mold-cavities, a screw-thread on the periphery of said plunger-flange, a ring surrounding said flange having a screw-thread co-operating with said flange-thread and means by which said ring may be turned to raise and lower said plunger and its flange and the plurality of ejectors.

10. In a machine of the character described, the combination of a lower mold-section having a central bearing and a plurality of radiating mold-cavities, a plunger with a concave upper face reciprocable in said bearing, an upper companion mold-section having a bearing in register with said first bearing and a plurality of complementary radiating mold-cavities, a plunger having a convex bottom face reciprocable in the bearing of said upper mold-section,

means to move said mold-sections toward and from one another relatively to open and close the complete mold-cavities, a slideable ejector associated with each of the mold-cavities of said lower mold-section, means to operate one of said plungers to force a portion of the molten-glass supply deposited on said lower plunger outwardly into said mold-cavities, and means to positively raise and positively lower said lower plunger and ejectors simultaneously and equally to deliver the glass casting from the lower mold-section.

11. In a machine of the character described, the combination of a lower mold-section having a central bearing and a plurality of blocks having radiating mold-cavities of different capacities, a plunger with a concave upper face reciprocable in said bearing, a companion mold-section having a bearing in register with said first bearing and a corresponding number of mold-blocks with complementary radiating mold-cavities, a plunger with a convex bottom face reciprocable in the bearing of said upper mold-section, means to move said mold-sections toward and from one another relatively to open and close the complete mold-cavities, means to depress the upper plunger to force a portion of the molten-glass supply deposited on the lower plunger outwardly into said mold-cavities, a slideable ejector associated with each of said mold-cavities, and means to slide said lower plunger and said ejectors simultaneously and equally to deliver the glass casting from the lower mold-section, the contacting faces of said mold-blocks sloping toward said plungers to compensate for their greater expansion nearest the central molten-glass supply.

12. In a machine of the character described, the combination of a pair of separable complementary mold-sections unitedly having a molten-glass supply-recess communicating with a plurality of mold-spaces, the contact face of at least one of said mold-sections sloping toward said recess to compensate for the difference in expansion throughout its extent, a mold-element in each of said mold-spaces, and means to simultaneously shift said mold-elements into operative or inoperative position.

13. In a molding machine, the combination of a reciprocatory water-cooled mold-section having a plurality of radiating mold cavities of different capacities, a series of air-cooled complementary mold-sections each having a central cavity to receive a charge of molten glass and a plurality of mold-cavities which are counterparts of those of said first mold-section and which communicate with said central cavity, and means to permit said first mold-section to be fitted to said complementary mold-sections in sequence, the contacting surfaces of said fitted mold-sections sloping

ing relatively to one another in varying degree depending upon the sizes of the mold-cavities to compensate for the greater expansion of the parts of the mold-sections nearest said cavity.

5 In witness whereof I have hereunto set my hand.

MARCH E. NAGLE.
